UNITED STATES PATENT OFFICE.

SIDNEY P. JONES, OF WACO, TEXAS, ASSIGNOR TO THE JONES ELECTRIC CORPORATION, OF WACO, TEXAS.

SHAVING MACHINE.

Application filed February 8, 1923. Serial No. 617,756.

To all whom it may concern:

Be it known that I, SIDNEY P. JONES, citizen of the United States, residing at Waco, in the county of McLennan and State of Texas, have invented certain new and useful Improvements in Shaving Machines, of which the following is a specification.

This invention relates to new and useful improvements in shaving machines.

10 The object of the invention is to provide a mechanical device for removing the beard from the human face in a simple, expeditious, convenient and comfortable manner.

A particular object is to provide a power 15 operated machine or device which will be substantially free from perceptible vibration and which will function efficaciously and without causing irritation or pulling of the hairs.

20 An important object of the invention is to provide a shuttle-action cutting blade which will cut thru the hairs in a diagonal direction when the device is moved over the face in a substantially straight line, thus 25 giving an easier and faster cutting action than can be had with an ordinary straight edge or safety razor.

Another object is to provide a shaving 30 device in which the shaving head may be moved in reverse directions while in contact with the face so as to shave in both directions in a quick and easy manner; and in connection with this feature is the provision of means for producing such a rapid 35 and smooth shuttle movement of a two edge blade, as to preclude any unpleasant or irritating results.

A still further object is to provide a cutter head arranged to accumulate and hold 40 the lather which is removed from the face, thus obviating the necessity of the use of paper or stopping to remove the accumulated lather, until the shave is completed.

Another object of the invention is to shut- 45 tle a two-edge blade between guard members, whereby either blade edge is free to cut the beard without overlapping or overlying the guard members.

A further object of the invention is to 50 provide a shaving device in which the blade may be readily removed and replaced and easily cleaned.

A construction designed to carry out the invention will be hereinafter described together with other features of the invention. 55

The invention will be more readily understood from a reading of the following specification and by reference to the accompanying drawings, in which an example of the invention is shown, and wherein:

Fig. 1 is a side elevation of a shaving machine constructed in accordance with my invention,

Fig. 2 is a front elevation of the same,

Fig. 3 is a longitudinal vertical sectional view of the same,

Fig. 4 is an elevation of the head with the guard plate swung down to expose the blade,

Fig. 5 is a similar view with the blade 70 and carriage removed,

Fig. 6 is a plan view of the machine,

Fig. 7 is a cross sectional view on the line 7—7 of Fig. 8,

Fig. 8 is an enlarged longitudinal sectional view of the head,

Fig. 9 is an enlarged fragmentary cross-section of the head, blade and carriage, and

Fig. 10 is a perspective view of the carriage.

In the drawings the numeral 10 designates a tubular handle having a head 11 at its upper end which is provided with a laterally offset bracket 12 extending longitudinally of the handle and head. The bracket is reduced in thickness to provide a web extending radially from the head and to form longitudinal lather holding channels or pockets 13 on each side. Guard members composed of transverse teeth 14 are disposed along each side of the face of the bracket; the teeth overhanging the channels and the spaces between the teeth forming entrances to the channels for the passage of the lather.

The face of the bracket has a pair of longitudinal grooves or trenches 15 contiguous to the teeth and a pair of spaced grooves 16, substantially parallel thereto (see Figs. 7 and 9). Between each groove 15 and its correlated groove 16 is formed a longitudinal runner or track 17. Longitudinally of the center of the face and between the grooves 16 is formed a longitudinal central

boss 18 having its surface below the surfaces of the tracks 17. Thus a cutting blade 19 mounted on the face of the bracket may rest entirely upon the tracks and free contact with the boss or other parts of the face of the bracket and while evenly supported by the spaced tracks, will shuttle with a minimum friction.

The teeth 14 and their relation to the cutting edges of the blade is very important. The outer surfaces of these teeth, which are brought into contact with the skin of the face being shaved, are curved outwardly from the side edges of the bracket to the edges of the blade, and are close together as is the practice in this art, said teeth being as narrow as the spaces. The cutting edges of the blade are contiguous to the inner ends of the teeth and overhang the grooves 15, whereby said edges are unobstructed, which is not the case where cutting edges overlap or overlie guard teeth. The cutting edges and the inner ends of the teeth being in substantially the same vertical plane and nearly coincident, a very safe and efficacious cutting action is had when the blade is shuttled or reciprocated longitudinally.

The blade is covered by a guard plate 20 having a hinge lug 21 at its lower end hinged between ears 22 at the bottom of the bracket. The plate has a stud 23 projecting from its upper end engaging a spring latch 24 fastened on the bracket (Fig. 8). The under side of the plate is dished longitudinally except at its ends so that its marginal edges bear up the blade and hold the latter upon the tracks 17. By springing the latch the plate may be quickly swung down (as in Fig. 4) to expose the blade 19. The blade is of such width as to expose the cutting edges of the blade which project beyond the edges of the plate. The outer surface of the blade is curved transversely, conforming generally to the curvature of the teeth, so that when the plate is pressed against the skin it may be rocked to either side to bring one of the cutting edges into contact with the beard. The plate provides a smooth guide or shoe for running the machine over the face.

The amplitude of the shuttle action of the blade may be confined within a fraction of an inch, a movement of substantially one-thirty-second of an inch having given satisfactory results in an extended period of experimentation, however the amplitude may be varied in accordance with the design of the machine.

Various means are obvious to those skilled in the art, for actuating the blade and it is possible to use many well known movements. I have used and here illustrate a shuttle carriage operated by an eccentric wheel, but even it is subject to variation. The carriage comprises an elongated carrier 25 which is substantially rectangular in cross-

section and fits snugly in a slot 26 extending inwardly from the face of the bracket, the slot connecting with a longitudinal bore 27 in which a cylindrical carriage 28 is mounted to slide.

The carrier has its underside concaved to fit on the carriage and is fastened to the latter by a screw 29 and a screw post 30 projects from the carriage thru an aperture 31 in the head. The carrier is shorter than the carriage and the parts are thus retained in their respective places. The outer portion of the carrier is reduced in width to form side ledges or shoulders 25' and the blade 19 is slotted so as to receive the carrier and rest upon the shoulders. The lower end of the carrier has an overhanging lip 32 (Figs. 8 and 10) and in placing the blade, the latter is tilted to first receive said lip and then is slid upwardly and pressed down on the shoulders. A turn button 32' is counter-sunk in the carrier and suitably shafted to ride out over the blade when turned crosswise. The lip and button act to hold the blade rigidly on the carrier and firmly upon the tracks 17. The blade may be quickly removed and replaced.

The head has an enlarged cavity 11' into which a bushing 33 mounted in the upper portion of the handle projects. This bushing is held in position by a set screw 33' or other means. A second bushing 34 is held in the handle by a set screw 34' or other means. A longitudinal shaft 35 extends thru the bushings and is provided with a pair of spaced collars 36 disposed between the bushings and abutting the ends thereof, whereby the shaft is held against longitudinal displacement. The upper end of the shaft has an annular groove 37 and projects into a bearing in the under side of a cap 39 confined in the upper end of the cavity 11' by a screw 38, the inner end of which extends into the groove 37.

On the shaft is mounted an eccentric wheel comprising a sleeve 40 and a pair of disks or annular flanges 41. The sleeve is suitably fastened upon the shaft with its lower end resting upon the upper end of the bushing 33, whereby end thrust is eliminated. The co-acting or adjacent sides of the flanges are dressed at an angle to transverse axis of the sleeve and are spaced to receive a roller 42 journaled on the inner end of the post 30 and spaced from the carriage by a washer 43 in the aperture 31. It will be seen that the flanges 41 form an eccentric and when revolved, impart a shuttle motion to the carriage thru the agency of the roller 42 and post 30.

The degree of inclination with respect to the transverse axis of the sleeve, which is given the sides of the flanges, is slight and is exaggerated in the drawings, as only a limited reciprocation of the blade is necessary.

sary. By revolving the shaft 35 at say seventy-five hundred R. P. M. the blade is shuttled rapidly and owing to the short amplitude of its movement and the firm 5 manner in which it is supported and guided, substantially no vibration is felt when using the machine.

The lower end of the shaft 35 is finished to receive the end of a flexible shaft 44, 10 which fits in the lower end of the handle 10 and is provided with a groove for receiving a spring pressed ball 45 projecting into the bore of the said handle, whereby the shaft 44 is held in engagement with the shaft 35. 15 A boss 46 (Fig. 3) cast on the side of the handle receives a set screw 47 which bears against a coiled spring 48 confined in the boss which has a bore for receiving said parts. The inner end of the bore is reduced 20 to less than the diameter of the ball 45, so while the spring pressed the ball into the bore of the handle, said ball is still retained in the bore of the boss.

In using the machine the beard is lathered in the usual manner and the machine started which is accomplished by attaching the handle to the flexible shaft 44, the latter being driven by an electric motor or other source of power (not shown). It is of 25 course within the province of the invention to mount an electric motor (not shown) in the handle 10 for the purpose of revolving the shaft 35. The shaft 35 being set in motion causes the blade 19 to shuttle by 30 reason of the reciprocation of the carriage 28 by the flanges 41. The operator grasps the head 11, the channels accommodating the fingers and thumb of the operator's hand. If desirable a knurled grip 49 may 35 be formed on the head at the lower end of one of the channels for the thumb. The machine is held transversely or at right angles to the position shown in Fig. 2 and with guard plate 20 in contact with face of the person 40 being shaved.

By rocking the head downwardly the lowermost teeth 14 and the lower cutting edge of the blade are brought into contact with the beard. The shaving is carried out 45 by a downward sweep of the head. Then rocking the head on the plate 20 the uppermost teeth and cutting edge are brought into contact with the beard and a reverse stroke may be made upward of the face. Various strokes may thus be executed and the shaving operation carried out in an expeditious, 50 satisfactory and pleasing manner.

As the shaving proceeds the shuttling of the blade will be so rapid that its movement 55 will not be felt upon the skin. The head being moved in a straight line the rapidly moving blade will cut diagonally, thus carrying out its work without pulling or irritation. As the lather is removed together with cut hairs it passes between the

teeth 14 and into the channels 13 which are ample enough to accommodate a full shave. When the shave is finished the machine may be subjected to a stream of hot water for cleansing.

70

What I claim, is:

1. In a shaving machine, an elongated handle member, a support extending longitudinally from the handle member, a web extending radially from the support, open 75 guards on each side of the outer portion of the web disposed in longitudinal relation to the handle member and support, a reciprocating cutting blade mounted on the outer face of the support and having its cutting edges between the guards, means in the support for imparting a shuttle motion to the blade, and a guard cover over a portion of the blade.

2. In a shaving machine, an elongated 80 handle member, a blade support disposed longitudinally of the handle member, and offset laterally a substantial distance therefrom, open guards on each side of the support, a shuttle blade mounted on the support between the guards, a radial web extending from the handle and spacing the support and guards therefrom, and means 85 for shuttling the blade.

3. In a shaving machine, an elongated 90 handle member, a blade support disposed longitudinally of the handle member and offset laterally a substantial distance therefrom, open guards on each side of the support, a shuttle blade mounted on the support between the guards, a radial web extending from the handle and spacing the support and guards therefrom, whereby lather 95 accumulating spaces are provided on each side of the web under the guards in communication with the openings of said guards.

4. In a shaving machine, an elongated 100 handle member, a blade support disposed longitudinally of the handle member and offset laterally a substantial distance therefrom, open guards on each side of the support, a shuttle blade mounted on the support between the guards, a radial web extending from the handle and spacing the support and guards therefrom, whereby lather 105 accumulating pockets are provided on each side of the web under the guards in communication with the openings of said guards and extending longitudinally thereof.

5. In a shaving machine, an elongated 110 handle, a head extending longitudinally from the handle, a shuttle blade supported in longitudinal relation to the handle, a 115 cover over the blade exposing the edges thereof, guards along each side of the blade and cover, the cover and guards being curved transversely for rocking on the face of the person being shaved for reverse shav- 120 125 130

- 4
- ing and offset radially from the handle to amplify the rocking motion, and means in the head for shuttling the blade.
6. In a shaving machine, a head, a bracket having its face offset from and extending longitudinally of the head, said bracket including a web extending radially from the head between the latter and the offset face, open guards along each side of the bracket outwardly of the web, said web providing spaces on each side thereof between the guards and the head, a shuttle cutting blade mounted on the face of the bracket, and means in the head for shuttling the blade.
- 10 7. In a shaving machine, a head, a bracket having its face offset from and extending longitudinally of the head, said bracket including a web extending radially from the head between the latter and the offset face, open guards along each side of the bracket outwardly of the web, said web providing spaces on each side thereof between the guards and the head, a carriage in the bracket, a shuttle cutting blade mounted on the carriage with its cutting edges between the guards, and means in the head for imparting a shuttle motion to the carriage and blade.
- 20 8. In a shaving machine, a head, a bracket having its face offset from and extending longitudinally of the head, said bracket including a web extending radially from the head between the latter and the offset face, open guards along each side of the bracket outwardly of the web, said web providing spaces on each side thereof between the guards and the head, a carriage reciprocating in the bracket, a shuttle cutting blade mounted on the carriage with its cutting edges between the guards, means in the head for imparting a shuttle motion to the carriage and blade, and a cover over a portion of the blade between its cutting edges.
- 30 9. In a shaving machine, a handle, a head extending longitudinally from the handle, a bracket having its face extending longitudinally of the head and including a web extending radially from the head between the latter and the face, a shuttle blade on the bracket, guards along each side of the bracket having openings communicating with the spaces on each side of the web of the bracket, the radial extension of the bracket web being such as to provide ample spaces under the guards to receive lather from a full shave.
- 40 10. In a shaving machine, a handle, a head extending longitudinally from the handle, a bracket having its face extending longitudinally of the head and including a web extending radially from the head between the latter and the face, guards along each side of the bracket having openings, the web having longitudinal channels along each side contiguous to the openings of the guards and providing finger room for the operator's fingers, a shuttle blade mounted on the face of the bracket, and means for imparting motion to the blade, the radial extension of the web being sufficient to provide channels ample for the reception of lather from a full shave.
- 50 11. In a shaving machine, a handle, a head extending longitudinally from the handle, a bracket extending radially from the head and having a slot in its face, a carriage reciprocating in the bracket, a carrier mounted on the carriage and extending through the slot of the bracket, a shuttle blade mounted on the carrier and extending over the face of the bracket, a cover on the bracket extending over the blade between its edges, means in the head for imparting a shuttle motion to the carriage, and open guards on each side of the bracket contiguous to the edges of the blade, the bracket being reduced in thickness between the head and the guards to provide lather accumulating spaces under said guards.
- 60 12. In a shaving machine, a handle, a head extending longitudinally from the handle, a bracket extending from the head and including a radially extending web longitudinally of the head, said bracket having its face offset from the head and handle and provided with a slot, said bracket having a longitudinal bore, a carriage mounted to reciprocate in the bore, a carrier mounted on the carriage and disposed in the slot, a screw post uniting the carrier and the carriage, a roller on the inner end of the post, a drive shaft in the head, a cam wheel on the shaft receiving the roller, a shuttle blade mounted on the carrier and extending over the face of the bracket, a guard plate on the bracket covering a portion of the blade and curved transversely of the bracket and at right angles to the edges of the blade, and guards mounted on the sides of the bracket contiguous to the edges of the blade.
- 70 13. In a shaving machine, a handle, a head mounted on the handle, a bracket mounted on the head in offset relation to the handle, a carriage mounted in the bracket, a two edge cutting blade mounted on the carriage, guard members on each side of the blade, means for imparting a shuttle movement to the carriage, and a guard plate fastened over a portion of the blade between the guard members, the bracket being reduced in thickness between the head and the guard members to form lather accumulating channels.
- 80 14. In a shaving machine, a tubular handle, a revoluble shaft mounted in the handle, a head mounted on the handle, a bracket offset laterally from the head, transverse guard teeth on each side of the bracket,

the bracket having lather channels on each side under the teeth, a carrier mounted to reciprocate in the bracket, grooves in the bracket contiguous to the teeth and on each 5 side of the carrier, a two-edged cutting blade mounted on the carrier and having its cutting edges overhanging the grooves contiguous to the teeth, a guard plate hinged on the bracket, means for fastening 10 the plate in contact with the blade, and means for imparting a shuttle movement to the carrier.

15. In a shaving machine, a tubular handle, a revoluble shaft mounted in the handle, a head mounted on the handle, a bracket offset laterally from the head, transverse guard teeth on each side of the bracket,

the bracket having lather channels on each side under the teeth, a carrier mounted to reciprocate in the bracket, grooves in the 20 bracket contiguous to the teeth and on each side of the carrier, a two-edged cutting blade mounted on the carrier and having its cutting edges overhanging the grooves contiguous to the teeth, a guard plate 25 hinged on the bracket, a carriage mounted to reciprocate in the bracket and to which the carrier is attached, a post projecting from the carriage, a pair of eccentric flanges mounted on the shaft, and a roller confined 30 on the post and engaging between the flanges.

In testimony whereof I affix my signature.
SIDNEY P. JONES.
